ANTENNA

Amory H. Waite, Jr., Long Branch, N. J.

Application December 11, 1943, Serial No. 513,871

4 Claims. (Cl. 250—33)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to antennas and more particularly to antennas for emergency use where the effective height of an antenna must be increased to improve the operating range of associated radio equipment.

In conventional use, vehicular or other portable antennas, because of structural considerations are limited in height. Thus, an operator, military or otherwise, is occasionally confronted with the necessity of obtaining communication from a location considerably beyond the normal operating ranges of such antennas and their associated transmitters and/or receivers.

Transmission and/or reception also suffer from line-of-sight obstructions when operating over hilly or tree covered terrain or locations having man-made obstacles.

It is well known to those versed in the art that propagation of radio waves, particularly at the higher frequencies, is greatly reduced and sometimes blocked if obstructions, natural or otherwise, exist in a transmission path at or above the level of the transmitting or receiving antenna.

Inasmuch as unfavorable geographical locations or ranges are selected for the operation of radio equipment only because an emergency exists, and the use of a more suitable location would be deemed inadvisable or imprudent, particularly in military operations, it was desirable that an antenna be designed to overcome natural or other barriers to the transmission or reception of high frequency signals, thus considerably increasing normal operating ranges.

In addition, the structural limitations of portable antennas are such that when operated on that portion of the frequency spectrum below approximately 15 megacycles, in conjunction with conventional antenna tuning circuits, outgoing or incoming signal strengths are proportional to the fraction of the overall electrical length of the antenna circuit which projects out of the vehicle as the antenna. Thus, it was desirable that an antenna be designed, which could cause a considerably greater fraction of the overall electrical length of an antenna circuit to project beyond the vehicle thereby greatly improving both the transmitting and receiving capabilities of the associated radio equipment.

Supports of a satisfactory height for antennas of various types, wire or otherwise, are on many

2

occasions difficult to obtain under field conditions and therefore it was necessary that the design of the antenna herein described serve not only as an antenna when required but also provide a raised support for another antenna, or antennas, all of which may be operated separately or simultaneously, anywhere in the radio frequency spectrum.

It was also essential that the antenna be of such construction that its easy transportation would be possible while using a minimum of space in whatever conveyance should serve as a vehicle for the associated transmitting and/or receiving equipment.

15 In addition it was deemed necessary that the erection of the antennas be simple, rapid, and require a minimum number of personnel.

The object of this invention is, therefore, to provide an antenna or antennas and/or a supporting structure capable of considerably increasing the communication ranges of one or more radio sets which normally utilize portable antennas.

20 A further object is to provide an antenna or antennas and a supporting structure which can be transported readily and occupy a minimum of space in a vehicle, and which can be economically and readily produced in quantity with present day methods of manufacture.

25 Another object is to make possible the erection and dismantling of the antenna or antennas and/or supporting structures rapidly, simply and with a minimum of personnel.

30 A still further object is to provide an antenna or antennas and supporting structures, adaptable to various uses and means of assembly and erection.

35 With these and other objects in view, many of which will become apparent from the following description of the illustrative embodiments of the invention shown in the accompanying drawings, the invention resides in the novel method, steps, elements, arrangement of parts in cooperative relation, as hereinafter more particularly pointed out in the claims; and exemplified in the practical embodiments of the structure herein described as follows:

40 Figure 1 is an elevational view of the antenna structure mounted on a bracket attached to a vehicle and used as a center-fed half-wave or elevated end-fed quarter-wave antenna for higher frequency operation.

45 Figure 2 is an elevational view of an antenna structure erected on the earth's surface and shows how the entire structure with its upper

whip extension could be used for lower frequency operation.

Figure 3 illustrates the intermediate and/or top and bottom gusset plates, together with a cross-sectional view of same.

Figure 4 depicts a combination gusset plate support for a whip type antenna, together with a cross-sectional view of same.

Figure 5 depicts a top gusset plate to accommodate an antenna base.

Figure 6 is a tubular member properly fitted at both ends, as illustrated, so they may be conveniently joined.

Figure 7 is an adapter used in conjunction with bolt Figure 8.

Figure 8 is a bolt used in conjunction with adapter Figure 7.

Figure 9 depicts an internally threaded and recessed cap screw which serves to fasten the bottom gusset plate Figure 3 to the tubular member Figure 6 of the structure.

Figure 10 illustrates a stud which is used to fasten top gusset plate to the tubular members Figure 6 of the structure.

Referring now more particularly to Figures 1 and 2:

Figure 1 illustrates the invention assembled as a structure for raising to a predetermined height a vertically polarized center-fed half-wave or elevated end-fed quarter-wave antenna for higher frequencies and comprises: gusset plates 16 and 27, which will be more particularly described as Figures 3 and 5; tubular members 11, same being illustrated in detail as Figure 6; adapter 12 and bolt 13 described hereinafter in detail as Figures 7 and 8 respectively; cap screws 14 described in detail as Figure 10; guys 15; snap hooks 16; studs 17 described in particular as Figure 9; a lower insulator 18; a vehicular mount 19 to support insulator 18; a coaxial cable 20; an insulator 21 supporting a whip antenna 22 and the entire structure attached to the body of the vehicle 23.

Figure 2 illustrates the invention assembled in its entirety as an antenna supported on a circular base 24, said base 24 being attached to a stake 25 driven into the earth and the entire structure being insulated from the earth's surface by insulator 26 and comprised of the following components: gusset plates 10 and 28 described in detail as Figures 3 and 4; tubular members 11 detailed as Figure 6; guys 15; snap hooks 16; whip antenna 22; cap screws 14 described more particularly as Figure 10; studs 17 detailed as Figure 9; trifurcated support 30 attached to gusset plate 10 and retained thereto by thumb screws 31; insulator 26; stake 25; circular base 24; lead-in 32.

Referring to Figure 3, same comprises a plate of ferrous or non-ferrous metal, or other material of equal tensile strength, having a predetermined thickness and of equilateral-triangular configuration. As illustrated in cross section the edges of this plate are rolled to give added strength to same. To those familiar with the art this equilateral-triangular configuration is known as a gusset plate and will so be referred to hereinafter.

Circular apertures 40, of predetermined diameter and disposed at the vertices of the gusset plate a predetermined distance from the perimeter of said gusset plate, are provided for insertion of the tubular members Figure 6 in a manner to be described hereinafter.

In the assembly and erection of the invention 75

the gusset plate Figure 3 is used as an intermediate or bottom member, the centrally located opening 41 will have a diameter which will permit passage of a coaxial cable or other conductor or can be used in a manner to be described hereinafter.

Spaced equidistant between the apertures 40 and around the perimeter of the gusset plate Figure 1 are orifices 42 of predetermined diameter. The aforementioned orifices 42 are provided for the insertion of snap hooks 16. Attached to the aforementioned snap hooks are guy wires 15 which are the means for supporting the antenna and/or mast in a vertical position.

10 A gusset plate Figure 4, has the same dimensions of the gusset plate in Figure 3 but differs therefrom with respect to the central perforation 43. This perforation 43 is extended axially by the addition of a hub 44 and the entire perforation 43 and contiguous hub 44 is internally threaded 45 its entire length. The particular purpose of this arrangement will be described hereinafter.

15 The gusset plate, Figure 5 is similar in all respects to gusset plates Figures 3 and 4 with the exception of the centrally located opening 44 which will have a diameter of suitable size to permit the insertion of an insulated whip antenna as will be described more particularly.

20 The apertures, openings, orifices and perforations, in the gusset plates, Figures 3, 4 and 5, are all disposed similarly and in the same relation to each other.

25 The tubular member Figure 6 comprises a tubular section 49 of ferrous or non-ferrous metal or other material having equal tensile strength, to one end of which is affixed, by method known to those versed in the art, a ferrule 50 of ferrous or non-ferrous metal or other material of equal tensile strength, the said ferrule 50 being knurled on the outer surface thereof for ease of manipulation. That portion 51 of the end of the tubular member 49 which is covered by the ferrule 50 is threaded internally a predetermined distance 30 therein. On the other end of the tubular member and opposite to ferrule 50 is attached a ferrule 52.

30 Figure 6 further illustrates in partial cross section the ferrules 50 and 52, their construction and the manner in which said ferrules 50 and 52 are attached to the tubular member 49. Extending from the ferrule 52 and immediately contiguous to same is an externally threaded portion 53 and another portion 54 split at the extreme 35 end a distance back therefrom to provide the necessary spring tension for a satisfactory electrical contact. The diameter of the threaded portion 53 immediately contiguous to the knurled portion 52 is such that any number of tubular members Figure 6 may be joined together in a manner to be described hereinafter.

40 An adapter Figure 7 is internally threaded 55 a distance therein and contiguous to this internally threaded portion 55 a recess 56 is provided to permit the insertion of the bolt Figure 8 in a manner to be described further along.

45 Immediately contiguous to and being a part of the threaded portion 55 and recessed portion 56 of the adapter Figure 7 is an externally threaded portion 57 and contiguous thereto, and also a part thereof, is a portion 58, split in the manner described hereinbefore. The upper portion 59 which is in juxtaposition to the internally threaded portion 55 is of hexagon configuration.

50 The bolt Figure 8 is conventional in design ex-

clusive of the end 60 which is contiguous to the threaded portion 61 and a part thereof. The aforementioned end 60 being similar to the split ends 54 and 58 already described.

The stud Figure 9 is conventional in design and the head 62 of same is knurled for ease of manipulation.

Figure 10 depicts a conventional type of cap-screw. However, the recess 63 is smaller in diameter than the internally threaded portion 64. The head 65 is knurled for easy manipulation of same.

The novelty of the invention resides primarily in the assembled structure and the ease with which same can be erected or dismantled together with the fact that the parts, as described herein and illustrated by the Figures 3 to and including 11, may be stowed away in a small bag in or on the outside of a vehicle and occupy a minimum of space.

The procedure for assembling the invention is comparatively simple. Referring to the completed structure in Figure 1 the following steps will describe the method used.

The gusset plate 10 is selected because its central aperture, as described heretofore as Figure 3, 41 is suitable for the insertion of the adapter nut and bolt 12 and 13 respectively. The adapter assembly 12 and 13 is affixed to the gusset plate 10. Following this the tubular members 11 are inserted in the apertures 40, of the gusset plate 10 as illustrated and the capscrews 14, of which there are three, although in Figure 1 only two are revealed, together with the one not shown are screwed on the threaded end 53 of the tubular members 11. Referring to Figure 6 and Figure 10 it can be readily observed how these two members are connected and the manner in which they retain the gusset plate 10 between them.

In the next step another gusset plate 10 is 40 placed with its apertured vertices contiguous to the threaded apertures 51 of the tubular members. With the gusset plate 10 in this position, the threaded ends 53 of another trio of tubular members 11 are screwed into and through the top of the apertured vertices 40 of the said gusset plate 10 and into the threaded apertures 51 of the first trio of tubular members 11.

The same procedure is followed until sufficient members have been assembled to the height desired.

The top gusset plate 27, Figure 5, is placed in the same relation to the tubular members 11, in the manner just described. The studs 17 are screwed into threaded opening 51 of the tubular members 11 and through the gusset plate 27, Figure 5. The purpose of the split ends 54, 58 and 60 of the various parts are so designed that the insertion of same into the various members of the structure depicted in Figure 1, make a good electrical contact. As will be noted the split ends are slightly larger in diameter at the lowermost ends thereof.

Referring again to Figure 1, the insulator 21 is inserted in the central aperture 44, Figure 5, of the gusset plate 27 and properly affixed thereto. To the lower end of the insulator 21 is attached the coaxial cable 20 and same is passed through the apertures 41 of the gusset plates 11 in this particular illustration. To the top of the insulator 21 is attached the desired antenna 22.

The aforementioned structure, Figure 1, after it is assembled, is mounted on the insulator 18 which is affixed to the mount 19 attached to the body 23 of the vehicle.

Prior to the placement of the structure Figure 1 on the vehicle mount 19, guys 15 together with snap hooks 16 are attached to the top gusset plate 27 and alternate gusset plates 10 in this particular illustration.

Moreover, the method of attaching the aforementioned guys and hooks depends entirely on the height of the structure erected.

The assembly, Figure 1, comprises a support for a vertically polarized antenna 22 or any other type antenna and the structure, Figure 1, itself is of course insulated from the antenna 22.

However, in Figure 2, the structure, as assembled and including the whip antenna 29, operates in its entirety as a radiator or receiver of electromagnetic energy.

The procedure in assembling the structure illustrated in Figure 2 is similar to that outlined in Figure 1. In this particular case the intermediate and bottom gusset plates 10 are alike. Gusset plate 28 is designed as illustrated in Figure 4 and is provided with an aperture 43 and a hub 44 which is contiguous thereto. This hub 44 serves to extend and strengthen the aperture 43 which is threaded internally as depicted. Into the aperture 43 is screwed the antenna 29. Thus the entire structure as assembled acts as a single radiator or receiver of electromagnetic energy. As illustrated in Figure 2 the main structure is supported by a trifurcated member 30 which is attached to gusset plate 10 and retained thereto by thumb screws 31. The trifurcated member 30 is attached to an insulator 26 and the insulator in turn is affixed to a stake 25. The stake 25 is centrally positioned thru the disc 24 and extends beyond the plane surface of said disc 24 a distance therefrom. The purpose of the said disc 24 is to permit the stake 25 to enter the earth a given distance therein and to add stability to the vertical position of the entire structure illustrated in Figure 2. As in Figure 1, further vertical stability is accomplished by using the guys 15 in a manner known to those versed in the art.

While there has been described what is at the present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An antenna, comprising a plurality of elongated tubular members composed of rigid material, a plurality of gusset plates of rigid material having the edges thereof rolled and containing therein a plurality of apertures, a portion of said apertures being disposed at the vertices of said gusset plates, the balance, with the exception of one aperture, being equidistantly disposed between the apertures located at the vertices of the said gusset plates, the exceptive aperture being centrally located in relation to the perimeter of said gusset plates, means for affixing the elongated tubular members at right angles to the gusset plates at the vertices thereof, means for combining the elongated tubular members and gusset plates to form a vertically disposed electromagnetic radiating structure, a supporting trifurcated member together with means for affixing same to the lowermost gusset plate of the combined structure, means for insulating the vertical electromagnetic radiating structure from the earth's surface and means for supporting

the combined insulating means and vertical structure on the earth's surface.

2. An antenna, comprising a plurality of elongated tubular members composed of ferrous or non-ferrous metal, gusset plates of ferrous or non-ferrous metal having the edges thereof rolled and containing therein a plurality of apertures part of which are disposed at the vertices of said gusset plates and part disposed equidistantly between the apertures at the vertices of the said gusset plates together with an opening centrally disposed in relation to the perimeter of said gusset plates, the said centrally disposed opening, in one of the plurality of gusset plates, having contiguous thereto a hub and the entire opening together with hub being threaded internally, means for affixing the elongated tubular members to the gusset plates at the vertices thereof, means for combining the elongated tubular members and gusset plates to form a vertical electromagnetic radiating structure, means for attaching an additional electromagnetic radiating member to the uppermost gusset plate of the structure, means for insulating the aforementioned structure from the supporting member and means for supporting the vertical electromagnetic radiating structure on a vehicle.

3. An antenna, comprising a plurality of elongated tubular members composed of electrically-conductive rigid material, gusset plates of electrically-conductive rigid material having the edges thereof rolled and containing therein a plurality of apertures part of which are disposed at the vertices of said gusset plates and part disposed equidistantly between the apertures at the vertices of the said gusset plates together with an opening centrally disposed in relation to the perimeter of said gusset plates, the said centrally disposed opening, of one of the plurality of gusset plates, having contiguous thereto a hub and the entire opening together with hub being threaded internally, means for affixing the elongated tubular members to the gusset plates at the vertices thereof, means for combining the elongated tubu-

lar members and gusset plates to form a vertical electromagnetic radiating structure, means for attaching an additional electromagnetic radiating member to the uppermost gusset plate of the structure, means for insulating the aforementioned structure from the supporting member and means for supporting the vertical electromagnetic radiating structure.

4. An antenna support, comprising a plurality of elongated tubular members composed of rigid ferrous or non-ferrous metal, gusset plates of rigid ferrous or non-ferrous metal having the edges thereof rolled and containing therein a plurality of apertures part of which are disposed at the vertices of said gusset plates and part disposed equidistantly between the apertures at the vertices of the said gusset plates together with an opening centrally disposed in relation to the perimeter of said gusset plates, the said centrally disposed opening, of one of the plurality of gusset plates, having contiguous thereto a hub and the entire opening together with hub being threaded internally, means for affixing the elongated tubular members to the gusset plates at the vertices thereof, means for combining the elongated tubular members and gusset plates to form a vertical structure, means for attaching an electromagnetic radiating member to the uppermost gusset plate of the structure, means for insulating the aforementioned structure from the supporting member and means for supporting the structure in a vertical position.
